LAMP

Gilbert A. Watrous, Chicago, Ill.

Application March 31, 1951, Serial No. 14,681

Term of patent 14 years

(Cl. D48—20)

To all whom it may concern:

Be it known, that I, Gilbert A. Watrous, a citizen of the United States, residing at Chicago, in the county of Cook and State of Illinois, have invented a new, original, and ornamental Design for a Lamp, of which the following is a specification, reference being had to the accompanying drawing, forming a part thereof, in which:

The dominant features of my design are shown in solid lines in the drawing.

I claim:

The ornamental design for a lamp, as shown and described.

GILBERT A. WATROUS.
